(57) **CLAIM**

We claim the ornamental design for a fastener with locking ring, as shown and described.

DESCRIPTION

FIG. 1 is a left side perspective view of a fastener with locking ring showing our new design with the locking ring installed on the fastener head portion;

FIG. 2 is a right side perspective view thereof;

FIG. 3 is a front elevational view thereof;

FIG. 4 is a rear elevational view thereof;

FIG. 5 is a left side elevational view thereof shown rotated ninety degrees to an upright position;

FIG. 6 is a left side perspective view thereof, shown without the locking ring;

FIG. 7 is a right side perspective view thereof, shown without the locking ring;

FIG. 8 is a front elevational view thereof, shown without the locking ring;

FIG. 9 is a rear elevational view thereof, shown without the locking ring;

FIG. 10 is a left side elevational view thereof, shown rotated ninety degrees to an upright position;

FIG. 11 is a left side elevational view of the locking ring shown at an enlarged scale;

FIG. 12 is a front elevational view of the locking ring shown at the enlarged scale;

FIG. 13 is a left side perspective view of the locking ring shown at the enlarged scale;

FIG. 14 is a right side perspective view of the locking ring shown at the enlarged scale; and,

FIG. 15 is an environmental left side perspective view of the Fastener with locking ring.

The broken lines in the drawings illustrate portions of the fastener with locking ring and form no part of the claimed design. The broken line showing of the shackle body in FIG. 15 illustrates the environment of the claimed design and forms no part thereof.
